GIRDLE

Pauline Z. Gordon, New York, N. Y.

Application November 3, 1948, Serial No. 149,446

Term of patent 3½ years

(Cl. D20—2)

To all whom it may concern:

Be it known that I, Pauline Z. Gordon, a citizen of the United States and a resident of the county, city, and State of New York, have invented a new, original, and ornamental Design for a Girdle, of which the following is a specification, reference being had to the accompanying drawing, constituting a part thereof, in which:

Fig. 1 is a front elevational view of a girdle, showing my new design;

Fig. 2 is a rear elevational view thereof;

Fig. 3 is a front elevational view of the girdle as it appears in opened position; and

Fig. 4 is a top plan view thereof as it appears in closed position.

I claim:

The ornamental design for a girdle, substantially as shown.

PAULINE Z. GORDON.
